UNITED STATES PATENT OFFICE.

ARTHUR TREVOR DAWSON, GEORGE THOMAS BUCKHAM, AND CARL ALFRED LARSSON,
OF WESTMINSTER, LONDON, ENGLAND, ASSIGNEES TO VICKERS, LIMITED, OF LONDON, ENGLAND.

AUTOMATIC GUN.

Application filed June 17, 1925., Serial No. 37,819.

To all whom it may concern:

Be it known that we, ARTHUR TREVOR DAWSON, GEORGE THOMAS BUCKHAM, and CARL ALFRED LARSSON, all subjects of the 5 King of Great Britain, residing at Vickers House, Broadway, Westminster, in the county of London, England, have invented certain new and useful Improvements in or Relating to Automatic Guns, of which the

10 following is a specification.

This invention relates to automatic guns, particularly those of the Vickers type.

According to the invention a hollow trunnion is provided on the cartridge feed side 15 of the gun and is made of sufficiently large bore to permit of the passage of ammunition through it to the cartridge feed mechanism of the gun, whereby avoiding difficulties which are at present sometimes experienced, especially with high angle guns, due to the carriage impeding the free entrance of the ammunition to the feed box of the gun. When belt or strip ammunition is used the other trunnion is also made hollow and of 25 sufficient bore to permit of the passage of the empty cartridge belt or the clips or links of the strip.

In order that the said invention may be clearly understood and readily carried into 30 effect, the same will now be described more fully with reference to the accompanying drawings in which:—

Figures 1, 2 and 3 are respectively a side 35 elevation, a front elevation and a plan shewing an automatic gun of the Vickers type, constructed in accordance with this invention.

A is the automatic gun trunnioned in a carriage B by means of hollow trunnions C, C. This carriage, in the example shewn, forms parts of a mounting of the pedestal type but it may equally well form part of a mounting of any other desired type.

The right-hand hollow trunnion is so 45 situated and of such a bore as to fully expose the cartridge feed opening in the mechanism casing (see Figure 1) so that a charged cartridge belt or strip can pass from a box D (attached to the trunnion) through the said trunnion to the cartridge feed mechanism. The empty belt in the case of a fabric belt (or the empty cartridge clips or links in the case of a strip composed of metal slips or links) passes through the left-hand

hollow trunnion. In the construction shewn 55 the two hollow trunnions are connected together by means of a web C' (Figure 2) which passes transversely beneath the mechanism casing of the gun, the unit thus formed being attached to the mechanism casing by 60 bolts c, c which pass through lugs c', c' on the hollow trunnions and through holes in the mechanism casing.

In some cases only one of the trunnions (i. e. that on the cartridge feed side of the 65 gun) need be made hollow; thus the usual feed box mouthpiece can be extended in a horizontal direction, or alternatively curved downwardly, the cartridges being urged into the feed box by a spring acting directly 70 or indirectly on the outermost cartridge in a similar manner to the magazine of an ordinary rifle. The usual feed levers provided in a gun of the Vickers type would ensure the 75 cartridge being carried into its correct position immediately over the barrel axis. It will be understood, of course, that the above described extension of the mouthpiece of the feed box can be a detachable hopper which contains the cartridges and which can be detachably connected to the feed box mouthpiece by suitable catches. In another arrangement which necessitates the provision of only one hollow trunnion the bore of the 80 hollow trunnion can be utilized to receive 85 a circular drum which may be of the usual pattern used in automatic guns of the gas operated type, this drum being detachably held by means of suitable catches. The said 90 drum contains one or more layers of cartridges placed radially and means are provided whereby a step-by-step rotary motion is imparted during firing so that the cartridges are ejected from the drum into the entrance of the feed box. The ordinary 95 feed levers provided in a gun of the Vickers type would then ensure the cartridges being carried into their correct position immediately over the barrel axis.

It will be seen that by reason of this invention the carriage will not offer any impediment at high angles of elevation of the gun to the free entrance of the ammunition to the feed box of the gun.

What we claim and desire to secure by Letters Patent of the United States is:—

1. In an automatic gun, the provision on the cartridge feed side of a hollow trunnion

of sufficiently large bore to permit of the passage of ammunition through it to the cartridge feed mechanism of the gun.

2. In an automatic gun, the combination with the mechanism casing, of a hollow trunnion of sufficiently large bore to permit of the passage of ammunition through it to the cartridge feed mechanism of the gun, and means for attaching said hollow trunnion to the mechanism casing.

3. In an automatic gun, the combination with the mechanism casing, of a hollow trunnion on the cartridge feed side of sufficiently large bore to permit of the passage of ammunition through it to the cartridge feed mechanism of the gun, a second hollow trunnion on the opposite side for the passage of the empty cartridge belt or the clips or links of strip ammunition, and means for attaching said hollow trunnions to the mechanism casing.

4. In an automatic gun, the combination

with the elements claimed in claim 2, of a box attached to the hollow trunnion for the reception of the charged cartridge belt or strip that is being fed through the hollow trunnion to the cartridge feed mechanism of the gun.

5. In an automatic gun, the combination with the elements claimed in claim 2, of a solid trunnion on the opposite side of the mechanism casing and means for feeding cartridges one at a time to the feed mechanism of the gun.

6. In an automatic gun, the combination with the elements claimed in claim 2, of a solid trunnion on the opposite side of the mechanism casing and means located within the hollow trunnion for feeding cartridges one at a time to the feed mechanism of the gun.

ARTHUR TREVOR DAWSON.
GEORGE THOMAS BUCKHAM.
CARL ALFRED LARSSON.
